UNITED STATES PATENT OFFICE.

CURTIS HUSSEY VEEDER, OF HARTFORD, CONNECTICUT, ASSIGNOR TO THE VEEDER MANUFACTURING COMPANY, OF HARTFORD, CONNECTICUT, A CORPORATION OF CONNECTICUT.

ODOMETER.

1,002,016.

Specification of Letters Patent. Patented Aug. 29, 1911.

Application filed January 12, 1911. Serial No. 602,193.

To all whom it may concern:

Be it known that I, CURTIS HUSSEY VEEDER, a citizen of the United States, residing in the city of Hartford, in the State 5 of Connecticut, have invented certain new and useful Improvements in Odometers, of which the following is a specification, reference being had to the accompanying drawings, forming a part hereof.

10 This invention relates to the means for actuating hub' odometers for motor and other vehicles which are mounted within casings secured to or forming parts of the hubs of vehicles to rotate therewith, the 15 actuation of the registering mechanism being effected through connections to the stationary axles upon which the wheels are mounted.

The invention is particularly concerned 20 with the actuating connections and has for its object to provide mechanism by which the register shall be driven in one direction only, while the mechanism itself is comparatively simple in construction and is 25 certain in operation.

The invention will be more fully explained hereinafter with reference to the accompanying drawings in which it is illustrated and in which—

30 Figure 1 is a view, partly in end elevation and partly in transverse section, of a wheel hub with the invention applied thereto. Fig. 2 is a view in section on the plane indicated by the line 2—2 of Fig. 1, looking in 35 the direction of the arrows. Fig. 3 is a view in section on the plane indicated by the line 3—3 of Fig. 1, looking in the direction of the arrows. Fig. 4 is a view similar to Fig. 1 but with some of the parts removed so as 40 to show others behind them more plainly.

Enough of a wheel hub *a*, of ordinary construction, is shown in the several figures of the drawings to enable the application of the invention to be understood, the end 45 of a stationary axle *b*, on which the wheel is mounted, being shown in Fig. 2. The hub is shown as having formed integrally therewith a cap *c* which forms a register chamber *c'*, separated from the axle chamber *a'* 50 by a plate *d* which is removably secured in the hub and supports the register *e* and, in

part, the driving mechanism. The end of the cap is provided with a glazed sight opening *c* through which the register may be read. 55

Any suitable form of register may be used provided it is adapted to be driven by the continuous rotation of its driving shaft *e'*, the invention being concerned not with the construction of the register itself but 60 with the construction of the driving mechanism therefor.

The driving shaft *e'* of the register has secured thereon a bevel gear *e* which meshes with a bevel gear *f* mounted loosely on a 65 shaft *g* which is supported in suitable bearings in the plate *d* and in the end of the cap. The shaft *g* has secured to its end, on the side of the plate *d* adjacent to the axle end *b*, an arm *h* which is slotted as shown by 70 dotted lines at *h'* in Fig. 1 for engagement with a pin *i* secured eccentrically to the axle *b*, so that as the hub rotates about the stationary axle the arm and shaft are oscillated. On the shaft *g* is secured a pawl carrier *g'* having one or more spring-pressed 75 pawls *g* which engage and are adapted to actuate a ratchet wheel *f'* secured to the hub of the gear *f*. In this manner the register *e* is driven through the oscillations 80 of the shaft *g* which are effected through the engagement of the stationary, eccentric pin *i* with the arm *h* which revolves with the hub. As effective movement of the pawl carrier is accomplished only by the complete 85 revolution of the shaft *g* and arm *h* about the stationary eccentric pin *i* and as the pin moves freely in the slot of the arm the register mechanism is not affected by the relative displacement of the hub and axle which 90 necessarily occurs.

It will be understood that the details of construction and arrangement may be varied to suit different conditions of use and that the invention is not restricted to 95 the precise construction shown and described herein.

I claim as my invention:

The combination with a wheel hub, of a 100 register supported by the hub, a shaft supported by the hub, an arm secured to the shaft and adapted for engagement with a

stationary eccentric pin carried by the axle, a pawl carrier secured to the shaft, a pawl carried thereby, a ratchet wheel mounted to rotate on said shaft and engaged by said pawl, a gear secured to said ratchet wheel and a register driving gear engaged by said last named gear.

This specification signed and witnessed this 10th day of January, A. D. 1911.

CURTIS HUSSEY VEEDER.
